MATTRESS TUFTING MACHINE

Walter H. Morley, Winnipeg, Manitoba, Canada

Application November 2, 1932, Serial No. 640,829
Renewed July 27, 1936. In Canada November
9, 1931

26 Claims. (CL. 112—3)

This invention relates to a machine for performing certain operations on a mattress, and particularly to a machine constructed and arranged for tufting mattresses. The machine is adapted for tufting different kinds of mattresses and both the inner-spring mattress and the felt filled mattress. In many mattress manufacturing establishments the tufting is done by hand, and the operation is thus quite slow.

- 10 It is an object of this invention, therefore, to provide a machine by the use of which an operator can easily, quickly and efficiently perform the tufting operation with the minimum amount of labor.
- 15 A further object is to provide a simply constructed inexpensive and durable machine which has but few parts to get out of order and which requires a minimum of floor space and which further has no relatively costly parts actively engaged with the mattress and liable to be broken.

20 A further object is to provide a machine by the use of which a very effective tufting job can be done on the mattress, the completed mattress having a finished appearance and the tufts tied so that there is practically no possibility of them working loose.

25 A further object is to provide a tufting machine wherein a tufting needle is used which is movable longitudinally of the mattress to complete a row of tufting, the mattress lying inert during such operation and wherein the mattress can be subsequently readily shifted to position for the starting of a following row of tufting.

30 A further object of the invention is to provide a machine with means for effectively compressing the mattress during the interval that a needle is being passed therethrough, a particular feature of the present invention being that pressure bars are used to compress the mattress for its entire length and hold it compressed during the interval that a row of tufting is being done from end to end of the mattress and are arranged also so that they can then be freed from the mattress to permit of the setting of the mattress as required for the starting of another row of tufting.

35 A further object of the invention is to provide a machine constructed to hold the mattress compressed during the interval that a needle is being passed in the manipulation of the machine through the mattress and which permits the operator to place by hand the looped tie string with an attached lower tuft or object in the eye of the needle after the needle has been projected

through the mattress and subsequently tie by hand manipulation the top tuft or object to the tie string after the needle has emerged from the upper face of the mattress.

It is a further object of the invention to provide a mechanism for compressing the mattress during the tufting operation and holding the mattress so compressed.

It is a further object of the invention to provide a machine having means for compressing the mattress and holding it compressed, together with means for piercing the mattress and carrying a flexible member therethrough which is movable throughout the length of the mattress so as to operate at different points thereon.

It is a further object of the invention to provide a simple and efficient method for tufting a mattress.

It is a further object of the invention to provide a mattress tufting machine having simple and efficient means for spacing the tufts, as well as simple and efficient means for gauging the tufts adjacent one end of the mattress.

These and other objects and advantages of the invention will be fully set forth in the following description made in connection with the accompanying drawings, in which like reference characters refer to similar parts throughout the several views and in which:—

Fig. 1 is a view taken substantially on line 30 1—1 of Fig. 4, as indicated by the arrow, some parts being further broken away;

Fig. 2 is a partial vertical section illustrating the method of carrying a tuft forming member through the mattress;

Fig. 3 is a view similar to Fig. 2, showing a subsequent step of the method;

Fig. 4 is a view in end elevation of the machine as seen from the left of Fig. 1;

Fig. 5 is a vertical section taken substantially 40 on line 5—5 of Fig. 1, as indicated by the arrows;

Fig. 6 is a top plan view of the machine;

Fig. 7 is a partial vertical section illustrating the method of passing a tape through the 45 mattress;

Fig. 8 is a similar view showing steps subsequent to that shown in Fig. 7;

Fig. 9 is a similar view of a later step, also illustrating the method and means used in tying the 50 tape;

Fig. 10 is a top plan view of a gauge member used;

Fig. 11 is a view in side elevation of said 55

member showing the carrying angle bar in section;

Fig. 12 is a partial section taken substantially on line 11—11 of Fig. 5;

5 Fig. 13 is a partial view similar to Fig. 5 shown on an enlarged scale.

Referring to the drawings, a machine is shown comprising a frame having end portions 11 and 12. While these portions could be made of various shapes and materials, in the embodiment of the invention illustrated each is shown as comprising a base member 11a and 12a respectively which is in the form of an angle bar and has its angle directed outwardly. Vertical members 11b and 12b extend upward from and are secured respectively to members 11a and 12a, said members having their angles directed outwardly and having one vertical flange directed rearwardly. Rear members 11c and 12c extend upwardly and forwardly from and are secured to base members 11a and 12a respectively, these members also having their angles directed outwardly and having one vertical flange directed forwardly. Members 11c and 11b are connected at their upper portions by a horizontal member 11d also illustrated as an angle bar having its angle directed inwardly and one flange extending inwardly. Members 11c and 11b are connected to member 11a by the headed and nutted bolts 13 and the members 12c and 12b are connected to member 12a by the headed and nutted bolts 14. Member 11d is connected to members 11b and 11c by the headed and nutted bolts 15 and said bolts also pass through and assist in securing to said members gusset plates 16. Additional headed and nutted bolts 17 pass through member 11d and gusset plate 16 and additional headed and nutted bolts 18 pass through the gusset plates 16 and members 11c and 11b respectively, securing said plates to said latter members. A top member 12d extends horizontally between the upper ends of members 12b and 12c, the same having its angle directed inwardly and being secured to said members by the headed and nutted bolts 19. Bolts 19 also extend through and assist in securing in place the gusset plates 20. Said plates are also secured to member 12d by the headed and nutted bolts 21 and to members 12d and 12c respectively by the headed and nutted bolts 22. End frames 11 and 12 therefore constitute similar trapezoids. Said end frames are connected at their upper ends by the front members or cross rails 23 and the rear members or cross rails 24 which extend between and are secured to members 11d and 12d. While members 23 and 24 might be made in various shapes, in the embodiment of the invention illustrated they are shown as made of angle bars having horizontal flanges engaging the horizontal flanges 60 of members 11d and 12d having their angles facing inwardly and their outer flanges extending vertically. Said members are connected to members 11d and 12d by angular clips or brackets 25 through which pass the bolts 26. The members 65 11c and 12c are braced and connected by the crossed bars 27 bolted thereto and connected at their central and crossing points by the bolt 28.

The members 11b and 12b have secured thereto at their upper portions and spaced forwardly a short distance therefrom, channel bars 29 and 30 respectively, said bars having their channels facing each other or inwardly of the machine and being spaced from the front vertical web of members 11b and 12b by the spacing bushings or 75 thimbles 31 through which pass the bolts 32 se-

curing said channel members in place. The heads of bolts 32 are countersunk in the flanges of channels 29 and 30 so that the inner sides of the channels are unobstructed. Said channel members have formed in their web portions adjacent the upper and lower ends thereof, elongated slots 29a and 30a respectively. A member 33 shown as an angle bar extends between the channel members 29 and 30 carried at its end by curved brackets 34 which are bolted by bolts 35 to guide blocks 36 having guide rollers 37 at their sides opposite said brackets which move in the channels of members 29 and 30 and are guided vertically therein. Another member 38 also shown as an angle bar extends between members 15 29 and 30 above member 33 and is connected at its ends to curved brackets 39 secured to the guide blocks 40 by bolts 41 which guide blocks have mounted thereon spaced rollers 42 also movable in the channels of members 29 and 30 and guided vertically thereby. Bars 33 and 38 have formed therein elongated slots 33a and 38a extending substantially from end to end thereof. Brackets 34 have their upper sides concave and are oppositely disposed to the brackets 39. Angle bars 33 and 38 have one flange extending horizontally forwardly and have their vertical flanges extending upwardly and downwardly in opposite directions and in the same plane. Blocks 36 have bolts 36a secured thereto extending outwardly through the lower slots 29a and 30a which pass through the upper ends of and hold in place the links 43. The upper ends of links 43 are disposed closely adjacent the outer sides of channels 29 and 30 and are bent outwardly closely adjacent said ends and have their lower ends pivotally connected by the bolts 44 to a double ended lever 45. The lower end of link 43 is curved forwardly and extends as shown in Fig. 4 around and beneath the shaft 46 to which both levers 45 are secured at the respective ends of the machine, said shaft being journaled in bearings 47 bolted to members 11b and 12b by the bolts 48. Levers 45 are rigidly secured to the shaft 46. The block 49 has a headed bolt or pin 49 projecting outwardly therefrom and extending through the upper slot 30a which passes through an aperture in the upper end of a link 50. The upper ends of links 50 are also disposed closely adjacent the outer sides of channel members 29 and 30 respectively and said links are bent outwardly just below said ends and extend downwardly at the outer sides of links 43 and have their lower ends connected by the pivot bolts 51 to the ends of the double arm levers 45 opposite the ends to which links 43 are connected. As shown in Figs. 4 and 5, the links 50 are disposed forwardly of links 43 and are curved rearwardly at their lower ends. Said links also extend forwardly and downwardly from their lower ends so that the vertical portion as shown 60 in Figs. 4 and 5 is in front of the channel members 29 and 30. One of the double arm levers 45 shown at the right hand side of Fig. 1 has a projecting hub from which extend radially and substantially at right angles to each other, handle arms 45a and 45b, the same having secured at their end portions the handles 52. The bar 33 has secured thereto in the corner of its channel blocks 53 preferably made of wood and one side of the hinge 54 is secured beneath each block, 70 the other side of said hinge being secured beneath the strip 55 on which is supported an open-work table 56. While this table may be made of various materials, in the embodiment of the invention illustrated it is shown as comprising 75

spaced side pieces 56a between which extend the spaced slats 56b. Another strip 57 extends lengthwise beneath the outer side of table 56 and has secured adjacent its ends angle brackets 58. Bars 59 illustrated as angle bars are secured to the brackets 58 and have their lower ends secured to the front of base members 11a and 12a respectively and by the bolts 13 and 14 respectively. The blocks 53 also have secured to their under sides one of the hinges 60, the other side of which is secured to a strip 61 which extends longitudinally beneath and supports another work table 62. While work table 62 may be variously made, in the embodiment of the invention illustrated it is composed of the side bars or strips 62a between which extend the spaced slats 62b. Another bar or strip 63 extends longitudinally beneath the outer edge of table 62 and has secured adjacent its ends a pair of caster brackets 64 carrying the caster wheels 65. Caster wheels 65 run upon the members 66 illustrated as angle bars having their vertical flanges secured by bolts 67 to members 11c, 12c and 11b and 12b and having their horizontal flanges facing inwardly and on which rollers 68 run. A rather wide strip or board 68 extends horizontally just above and parallel to members 66 and is also secured by screws 69 to the end frame members 12c and 12b. The member 68 extends from members 12b rearwardly of the machine and has its rear edge alined with the rear end of member 66. Another plate or board 68a is provided, similar to board 68, and of the same length. Board 68a is carried by and has secured thereto a pair of parallel rods 68b which rods are joined at their ends by a cross piece 68c having formed therein a grip handle 68d. Rods 68b are guided in bores drilled in a plate 68e having bosses 68f projecting outwardly therefrom. Rods 68b are slideable through said bores so that board or plate 68a can be moved to different positions as indicated in dotted lines in Figs. 1 and 6, always remaining at right angles to strip 63 and thus be disposed at different distances from the end of the machine. Bars 68b each have formed therein a series of holes 68g adapted to be engaged by the downwardly turned ends 68h of resilient or spring arms 68i secured to the cross member 68e, said projections 68h extending downwardly through the bosses 68f. With the described construction, plate 68a can be moved lengthwise of the machine in parallel relation to plate 68 and can be held in any one of several positions by means of spring arms 68i.

A carriage 70 is provided, movable longitudinally of the frame of the machine on members 23 and 24, which carriage is shown as comprising side members 70a illustrated as made from angle bars having one flange horizontal and their angles directed away from each other, the vertical flanges extending downwardly from the horizontal flanges. Bars 70a are connected by the cross bars 70b and are further connected at their central portions by a bar 71 illustrated as in the form of a T bar with its central web extending vertically. A bar 72 of flat form rectangular in cross section extends vertically from the front of said carriage, the same being secured to the front member 70a and to member 71. Bar 72 has secured to its front side a bracket 73 having forwardly extending lugs 73a at its top and bottom apertured to form guides for a vertically movable plunger 74 shown as cylindrical in form. Plunger 74 has a block 75 secured thereto, the sides of which are embraced by down- wardly extending arms disposed at either side of a yoke bracket 76 embracing plunger 74 and bracket 73 and having projecting outwardly therefrom a handle 76a. Yoke bracket 76 has projecting rearwardly from its yoke or open portion an arm 76b. Arm 76b has pivoted at either side thereof by a pivot bolt 78a, the upper ends of a pair of links 78, the lower ends of which are disposed at either side of the web of bar 71 and pivoted thereto by the pivot bolt 79. The bar 72 has at its upper end a pair of rearwardly and horizontally projecting spaced arms 72a and the upper ends of a pair of springs 77 are connected respectively to these arms, the lower ends of said springs being connected to arms 76b just rearwardly of the yoke portion of the bracket 76. The plunger 74 has secured to its lower end a block or holder 80 to which is removably secured a needle 81, said needle being held in place by a screw 82 and being removable by loosening said screw. Needle 81 is sharpened at its lower end and has formed in one side an open ended slot or eye 81a which extends at an angle to the axis of said needle. The angle members 70a have secured therein adjacent each end thereof studs 83 on the lower ends of which are journaled rollers 84 disposed to engage the inner sides of the vertical flanges of angle bars 23 and 24. Said angle bars 70a also have secured in their vertical flanges a short distance from studs 83, the studs 85 on which are journaled rollers 86 disposed to engage the top of the horizontal flanges of angle bars 23 and 24. The angle bars 70a also have secured at the outer sides of the angles and to the vertical flanges depending brackets 87. Brackets 87 have horizontally disposed studs 88 therein on which are journaled rollers 89 disposed to engage the bottoms of the horizontal flanges of angle bars 23 and 24. From the description it will be seen that the carriage comprising the angle bars 70a is thus supported by the rollers 86 on the angle bars 23 and 24 and is guided in a rectilinear path by rollers 88 and is prevented from moving vertically by the rollers 89. The carriage thus rolls easily along the members 23 and 24.

The carriage 70 has secured thereto in the rear of bar 72 a hollow casing 102 bored to receive a vertically movable plunger 103 having a pin 104 secured therein and projecting at one side thereof, which extends through a slot 102a in the side of casing 102. A compression coil spring 105 is disposed in casing 102 engaging the top of plunger 103 at one end and engaging at its upper end the plug 106 threaded into the top of casing 102 and having an angularly shaped projecting portion adapted to be engaged by a wrench. Plunger 103 is forked at its lower end and has secured thereto in a pin 107 on which is journaled a small roller 108. The roller 108 is adapted to engage in any one of a plurality of semi-cylindrical notches 109a formed in a bar 109 which is substantially square in cross section. The notches 109a are disposed midway between the sides of the bar and there is a series of such notches on each side of said bar. Bar 109 extends through an opening in the upper portion of the T-shaped member 71 and extends from end to end of the machine above member 23, the same having adjacent its ends reduced portions journaled in brackets 110 mounted on the end members 11d and 12d. At the left hand end of the machine as seen in Fig. 1 bar 109 has secured thereto a disc 111 having on its outer face and spaced 90 degrees apart, the numbers 5, 6, 7, and 8. Disc 111 is provided with notches 111a also spaced 90 degrees

apart, any one of which is adapted to be engaged by the projection 112a extending from a spring lever 112 secured to one of the brackets 110. Shaft 109 can therefore be rotated by means 5 of the disc 111 and maintained with any one of its sides uppermost and adapted to be engaged by the roller 108.

As shown in Figs. 7 and 8, the plunger 74 may have secured thereto a head 90 having secured 10 therein a pair of needles 91 and 92 removably held in said head by the screws 93. Needle 91 has an open ended slot or eye 91a adjacent its lower pointed end, said slot extending downwardly into said needle at an angle to the axis 15 thereof. Needle 92 has an open ended slot or eye 92a adjacent its lower pointed end and this slot extends upwardly in said needle toward its bottom at an angle to the axis of said needle.

In Fig. 9 a gauge member or dolly 94 is shown, 20 over which the tape is tied in the tape-tying operation. In Figs. 10 and 11 another type of gauge or dolly is shown, which comprises a substantially elliptical or oblong member 114 which is provided with an opening at its lower end so 25 that member 114 can be placed on the vertical flange of member 38 as shown in Figs. 10 and 11. An arm 114a extends forwardly from the oblong portion of member 114 and the member 114b projects some distance at either side of arm 114a, 30 the same being oblong in vertical cross section. Member 114b extends parallel to the vertical flange of member 38.

In operation when a mattress, designated 101, is to be tufted, the same is placed upon the table 35 62 and at this time the members 33 and 38 are separated and in a position shown in Figs. 1 and 4 and plunger 74 is elevated as shown in Figs. 1 and 4. One side of the mattress is supported over the bar 33 and extends between bars 33 and 40 38 onto the narrower work table 56. The line in which the tuftings or tufts are to be formed is disposed between the bars 33 and 38 and in alignment with the line connecting the centers of openings 33a and 38a. The number of tufts in 45 various mattresses vary; in some there are five tufts spaced lengthwise of the mattress, in others six, and in others there may be seven or eight. The operator first positions board or plate 68a in the desired position to give the number of tufts 50 desired. In positioning plate 68a the operator first lifts spring arm 68i so that their downturned ends 68h are removed from the holes 68g thus releasing rods 68b for sliding movement. The operator now grasps the handle 68d and pushes 55 inwardly or pulls outwardly thereon as desired to move plate 68a to the desired position. When said plate is properly adjusted the ends 68h of the spring arms 68i will again move downwardly into a pair of the holes 68g and rods 68b will 60 again be locked in position with plate 68a in the desired position. The operator now moves the end of the mattress against the plate 68a and the mattress is in position for the placing of the first tuft. It will be understood that the operator 65 will turn the wheel or disc 111 by moving out member 112 so that the bar 109 has its proper side turned upward. If there are to be five tufts spaced lengthwise of the mattress, the numeral 5 will be placed upward at the top of the disc 70 and if other spacing is desired, the other numbers will be accordingly brought to the top. The mattress being thus positioned, the operator takes hold of one of the handles 52 and moves the same in a clockwise direction as shown in Fig. 5. 75 This rotates shaft 46 and the double ended levers

45 and the rotation of oscillation of the levers 45 moves links 43 upwardly and moves or pulls links 50 downwardly. The operator can use both handles 52 if convenient and the levers 45 are brought to the position shown in Fig. 5 so that 5 the pivots 51 are moved to the right of the vertical center line through the axis of shaft 46 and pivots 44 are moved to the left of the vertical center line through shaft 46. These pivots are thus past dead center and the links 43 and 10 50 as well as bars 33 and 38 are locked in position. The said movement of links 43 and 50 causes the bars 33 and 38 to move toward each other and compresses the mattress therebetween as indicated by the dotted lines in Fig. 5. The 15 mattress is thus compressed to compact and small thickness between the horizontal flanges of bars 33 and 38 and it is held in this position owing to the locking action of the links 43 and 50. The operator now takes hold of the lever 76a 20 and moves the carriage longitudinally of the machine to one end of the mattress, the needle 81 moving longitudinally over member 38 and in the line of the centers of the openings 33a and 38a. The carriage is moved until roller 108 engages 25 in end notch 109a and the carriage is then in position for the first tuft to be made. The position of member 68a will determine the position of the first tuft. This first tuft will be at the same distance from the end of the mattress as 30 the first notch 109a is from member 68a. The operator now pulls downwardly on handle 76a and needle 81 pierces the mattress and passes therethrough and through the openings 33a and 38a as shown in Fig. 2. The operator now takes 35 a tufting cord 95 which is looped as shown in Fig. 2 and has secured to one end of the loop a button or head member 96. The operator places the end of the loop in the eye 81a and then allows lever 76 to move upwardly under the tension of 40 springs 77 which were distended when handle 76a was moved downwardly. Needle 81 is retracted and moves upwardly through and out of the mattress to the position shown in Fig. 3. As the needle 81 moves up through the mattress 45 it pulls with it the cord 95. The operator now takes a button 97 having a staple 98 thereon, passes the end of the loop through the staple 98 and moves the end over the button 97. The button is now held on the cord or loop 95. When 50 this operation is completed, the operator moves to the next opening 38a in which it is desired to place the tuft and the operation is repeated. The carriage 10 rolls freely on members 23 and 24 and the operator merely holds the handle 76a 55 in moving the carriage and plunger to the next position to bring the needle to the next position. As the carriage is moved, the roller 108 rolls along the top of the bar 109 and when a slot or pocket 109a is reached, roller 108 snaps into this slot. 60 The roller, of course, was in one of the slots for the first tuft made, and it will successively engage the slots as the carriage is moved. It may be stated that it is the common practice to take every other slot for one row of tufts, and then 65 take the alternate slots in making the next row of tufts. By this operation the tufts are staggered in the mattress. There are thus twice as many of the slots 109a as there are indicated by the numbers on the disc 111. The tufts are thus 70 made lengthwise of the mattress for the full length thereof and when the row has been completed, the operator steps to the end of the machine and again rotates the handle levers 45 and swings the double ended lever arms to the 75

position shown in Fig. 4. When this is done, the bars 33 and 38 are moved apart and the mattress resumes its natural thickness and the cord 95 is stretched between the members 96 and 97 and the tufts are completed. The cords 95 are of uniform length and the tufts will therefore all be uniform throughout the row. It will be noted that in this position the pivots 51 are at the left of the vertical line passing through the axis of shaft 46 and the pivots 44 are to the right. Bar 38 is thus held in its upper position as the pivot bolt 36a is at the bottom of the lower slot 39a. The mattress is now moved forwardly to bring it to the position where another row of tufts will be made and the operator again rotates the lever arms 45a and 45b by the handles 52 to again compress the mattress. The rows of tufts are thus made successively, the mattress being moved for each row. The mattress can be reversed after half of the rows are placed therein, so that the main part of the mattress is for the greater part of the time on the wider table 62. The tufting of the mattress is thus completed in a very short time.

One form of tufting known as tape-tufting, is illustrated in Figs. 7 to 9. With the present machine this is accomplished by the use of a double needle as illustrated in said figures. When the mattress has been compressed between the members 33 and 38, the operator takes the piece of tape 100 which has been cut to the proper length and places it in the eye 92a of the needle 92 having a short length of the tape projecting at one side of the needle. He then pulls down on the lever 76a moving both needles through the mattress and the tape is drawn downwardly and through the mattress by needle 92. Both needles are now projecting below the mattress and the operator takes hold of the end of the tape 100 removing the same from the slot 92a and moving it around the other needle 91 and into the eye 91a. This can be done very quickly, and the tape then occupies the position in needle 91 shown in Fig. 8. The operator now releases lever 76a, the needles are moved upwardly through the mattress, and the tape is carried upwardly by needle 91 and drawn through the mattress. The tape now extends through the mattress in parallel lines with the bight at the middle portion of the tape on the under side of the mattress as shown in Fig. 9. A gauge or dolly 94 is used, which is placed on the bar 38. The operator now ties the desired knot 100a in the tape at the top of member 94, the knot being drawn up so that the tape is fairly taut over member 94. The operator then moves the carriage to the next position and repeats the operation. When the row of tufts has been made, members 33 and 38 are moved apart as above described and the mattress resumes its normal width. The tufts are made by the tape 100 extending through the mattress and all of the tufts will be uniform due to the fact that a uniform length has been made between the bight of the tape and the knot therein, as above described. The slots in needles 91 and 92 are made to converge toward their ends so as to be substantially wedge shaped. With this construction, the tape wedges in the slot and is conveyed through the mattress without slipping in the needle.

When the gauge member 114 is used, it is merely placed on the member 38 and can be slid along on this member as it is needed. The tape can be tied over the member 114b at either side

of the arm 114a. Said gauge member slips easily from the tape.

It will be noted that the member 33 has vertical movement in the guide members 29 and 30 and there is thus some movement of the outer end of the table 62. In this movement the roller 65 merely runs on the bar 66. There is likewise some pivotal movement of the table 56 and this is accommodated by movement of the bars 59 which are pivoted at their upper and lower ends.

From the above description it is seen that applicant has provided a very simple, easily operated and efficient machine for tufting mattresses. The operator soon becomes quite skillful in placing the cord members 95 in position and placing the buttons thereon, as well as in manipulating the tape 100 in the tape-tufting operation. The mattress is conveniently supported and the carriage 70 is quite easily moved to bring the needles into the desired position. The tufting operation can be completed in a small part of the time necessary to perform the same by hand. The tufting is thus very quickly done and the tufts are all uniform. It is impossible to get all the tufts uniform when the tape tufting is done by hand. At the same time the machine comprises no complicated or expensive mechanism. The machine has been amply demonstrated in actual practice, and found to be very successful and efficient.

It will, of course, be understood that various changes may be made in the form, details, arrangement and proportions of the apparatus and in the steps and sequence of steps of the method without departing from the scope of applicant's invention, which, generally stated, consists in a method and apparatus capable of carrying out the objects above set forth, such as disclosed and defined in the appended claims.

What is claimed is:—

1. A mattress tufting machine having in combination, a pair of clamping members adapted to be disposed respectively on opposite sides of the mattress, means for moving said members toward each other to compress and hold said mattress, said members having openings therethrough, a plunger reciprocal above said members, means carried by said plunger for passing through said openings and piercing said mattress, said means being constructed and arranged to carry a cord or flexible member through said mattress, and means for operating said plunger.

2. A mattress tufting machine having in combination, a frame, means for engaging and supporting a mattress, comparatively narrow clamping members extending across said mattress disposed on opposite sides thereof and having aligned openings therethrough, means for moving said members to compress a mattress and hold the same compressed along a narrow zone extending across the same, a carriage mounted on said frame for travelling movement longitudinally of said members, a plunger reciprocal in said carriage above said members, and means carried by said plunger movable through said openings for piercing said mattress and conveying a flexible member therethrough.

3. A mattress tufting machine having in combination, a frame, a member for supporting and clamping one side of the mattress, guide means in said frame in which said member is vertically movable, supporting members for said mattress pivoted to opposite sides respectively of said

- member, a second clamping member above said member, means for moving said clamping members toward each other to clamp said members and hold the same in said clamped position, said members having aligned openings therethrough, a plunger reciprocable in alignment with said openings, and piercing and cord carrying means carried by said plunger adapted to pass through said openings and mattress.
10. A mattress tufting machine having in combination, a pair of members extending longitudinally of the machine and adapted to be moved apart and moved together for clamping and compressing said mattress, a carriage movable longitudinally of said machine, mattress piercing means carried by said carriage, a bar extending longitudinally of said machine having spaced depressions thereon, and means on said carriage for engaging said depressions to determine the points at which the mattress is to be pierced.
15. The structure set forth in claim 4, said bar having a plurality of sides and means for turning said bar to bring different sides into position to be engaged by said last mentioned means, the depressions in the different sides of said bar being differently spaced.
20. A mattress tufting machine having in combination, means for compressing a mattress and means for piercing said mattress comprising a pair of pointed needles having points therein with an open slot extending into each of said points, said slot in one of said needles being directed upwardly at an angle to the axis of said needle and the slot in the other needle being directed downwardly at an angle to the axis of said needle.
25. The structure set forth in claim 6, a member to which both of said needles are secured at their upper ends and said slots in each of said needles being disposed at the side of said needle remote from the other needle.
30. A mattress tufting machine having in combination, a frame, a table for supporting a mattress, clamping means for said mattress adjacent the edge of said table, means for piercing said mattress and carrying a tufting member therethrough, an auxiliary table for said mattress at the side of said clamping member opposite said first mentioned table, said clamping member being vertically movable and said tables being hingedly connected thereto.
35. The structure set forth in claim 8, a horizontal support on said frame, the side of said first mentioned table remote from said clamping member being carried on and movable toward said clamping means on said support in the clamping operation.
40. A mattress tufting machine having in combination, means for compressing and holding a mattress and means for piercing said mattress comprising a pair of pointed needles each having an eye therein, the eye in one needle having an open portion directed upwardly and the eye in the other needle having an open portion directed downwardly.
45. The structure set forth in claim 10, said needles being disposed adjacent each other in parallel relation, said eyes being adjacent the pointed ends of said needles and disposed at the side of each needle remote from the other needle.
50. A mattress tufting machine having in combination, means for engaging and supporting a mattress, means for clamping and compressing said mattress along substantially a line extending across said mattress, means movable longitudinally of and above said clamped and compressed portion of said mattress and means carried by said last mentioned means for piercing said mattress to insert tufts therethrough one at a time.
55. A mattress tufting machine having in combination, means disposed above and below said mattress respectively for clamping and compressing said mattress in a narrow zone extending thereacross, means at one side of said mattress movable longitudinally along said zone and vertically movable means carried by said last mentioned means for piercing said mattress and at said zone inserting tufts therethrough one at a time.
60. A mattress tufting machine having in combination, means for supporting a mattress in laterally stationary position means movable across said mattress while the same is stationary and carrying means for piercing said mattress to form tufts therein, a member for determining the positions of said tufts and means engageable by the end of the mattress for positioning the mattress relatively to said member to locate said tufts on the mattress and means for holding said last mentioned means in different positions.
65. A mattress tufting machine having in combination, means disposed above and below said mattress respectively and movable toward said mattress for clamping and compressing said mattress in a narrow zone extending thereacross, means at one side of said mattress movable longitudinally along said zone for vertically piercing said mattress and inserting tufts therethrough one at a time, and means cooperating with said second mentioned means for determining the positions of said tufts.
70. A mattress tufting machine having in combination, means disposed above and below said mattress respectively and movable toward said mattress for clamping and compressing said mattress in a narrow zone extending thereacross, means at one side of said mattress movable longitudinally along said zone, vertically movable means carried by said last mentioned means for piercing said mattress and inserting tufts therethrough one at a time, and a bar for determining the location of said tufts, said bar having means thereon for giving definite spacings of said tufts.
75. In a mattress tufting machine, the combination of a supporting framework, a mattress supporting table supported by said framework, a pair of compressor members slidable vertically in the framework and movable downwardly toward the plane of said table and upwardly toward the plane of said table respectively, a lever for shifting said compressor members and a self-locking linkage between said lever and said members.
80. In a mattress tufting machine, the combination of a supporting framework, a substantially horizontal mattress supporting table supported by said framework, a pair of compressor members slidable vertically in the framework above and beneath a mattress supported on said table respectively, a manually operated lever for shifting said compressor members and a self-locking linkage between the lever and said members.
85. A mattress tufting machine having in combination, a frame, a mattress supporting table carried by said frame, a pair of compressor members slidable vertically in said frame above and beneath a mattress supported on said table, means for moving said members to compress said mattress including self-locking means holding said members in said position and means for

spotting the points for tufts to be made in said mattress.

20. In a mattress tufting machine, the combination of a supporting framework, a mattress supporting table supported on said framework, a pair of compressor members of a length to extend across said table slideable vertically in said framework above and beneath a mattress supported on said table so as to compress a narrow zone across 10 said mattress and means for spotting the points for the tufts to be made in said mattress whereby the spacing between said tufts may be made uniform.

21. The structure set forth in claim 20, said last mentioned means comprising a member having spacing indications thereon and adapted to be moved to indicate a different number of equally spaced tufts across said mattress.

22. A mattress tufting machine having in combination, a pair of clamping members adapted to be disposed respectively on opposite sides of the mattress, means for moving said members toward each other to compress and hold said mattress, said members having openings therethrough, a 25 plunger reciprocable above said members, a needle carried by said plunger adapted to pass through said openings and pierce said mattress, said needle having a slot therein open at one side thereof adapted to receive a flexible member for 30 conveying the same through said mattress.

23. A mattress tufting machine having in combination, a frame, means for engaging and supporting a mattress, comparatively narrow clamping members extending across said mattress disposed on opposite sides thereof and having aligned openings therethrough, a carriage mounted on said frame for travelling movement longitudinally thereof and of said members, a plunger reciprocable in said carriage above said members, means 35 carried by said plunger movable through said openings for piercing said mattress and conveying a flexible member therethrough, manual means for depressing said plunger and automatic means for elevating said plunger.

45. 24. A mattress tufting machine having in combination, a mattress support, a pair of clamping members disposed respectively on opposite sides of a mattress carried on said support, said mem-

bers each being movable toward said mattress and a common operating means for moving said members toward said mattress to clamp the same therebetween, said members having aligned openings therethrough, a plunger reciprocable above 5 said members and means carried by said plunger for passing through said openings and piercing said mattress, said means being constructed and arranged to carry a cord or flexible member through said mattress and means for operating 10 said plunger.

25. A mattress tufting machine having in combination, a frame having spaced end members, a mattress support, a pair of clamping bars each extending across said mattress from one side to 15 the other and each having a vertically extending opening therein aligned vertically respectively with the opening in the other, guiding means in said end members for said clamping bars, said clamping bars being movable toward said support, 20 members connected to said clamping bars respectively and a means to which said last mentioned members are connected for simultaneously moving the same and said clamping bars towards each other to clamp a mattress therebetween, a 25 plunger movable on said frame lengthwise of said clamping bars to align with said openings therein, means for reciprocating said plunger and a needle carried by said plunger for piercing said mattress to carry a cord or flexible member through said 30 mattress.

26. A mattress tufting machine having in combination, a frame having spaced end members, means for engaging and supporting a mattress, bars extending between said end frames for 35 clamping and compressing a mattress supported on said means, means for moving said bars toward each other to clamp and compress said mattress, a cross rail extending between said end members above said bars, a carriage guided and movable 40 on said cross rail longitudinally of and above said bars, a plunger carried by said carriage and vertically movable therein, a needle carried in the lower end of said plunger and means for depressing said plunger to move said needle through a 45 mattress clamped and compressed by said clamping means.

WALTER H. MORLEY.
